VENDING MACHINE

Lee M. Moninger, Los Angeles, Calif.

Application May 17, 1937, Serial No. 142,945

10 Claims. (Cl. 312—63)

This invention relates to dispensing machines and has for an object the provision of a vending machine capable of dispensing different quantities of the article being vended as determined by the manner in which the dispensing machine is operated. The device of the present invention therefore represents an improvement over that forming the subject matter of United States Letters Patent No. 1,952,244, issued March 27, 1934, to Clarence F. Grim.

A more detailed object of the present invention is to provide a dispensing machine operable upon the principles indicated, but adapted to dispense packaged goods such as packages of cigarettes.

A still further object is to provide a machine of the general character described, provided with a plurality of storage magazines from any of which the operator can cause articles to be vended, whereby supplies of each of several different articles or of several different kinds or brands of the same article can be made available to the operator. Thus he is enabled to select whichever article or brand he may desire or to receive a variety of the articles in the event he has operated the machine in such a manner as to entitle him to more than one.

A further object is to provide a dispensing machine as described, the operating mechanism of which is of exceedingly simple characteristics and yet amply rugged and durable to insure satisfactory operation over an extended period of time and so fully dependable in its operation as to practically exclude all possibility of the receipt by unauthorized persons of the article being vended thereby.

A still further object is so to simplify the entire machine that its cost of production is reduced to a minimum without any impairment to the efficiency of its operation.

The invention possesses other objects and features of advantage, some of which, with those enumerated, will be set forth in the following description of the preferred embodiment of my invention which is illustrated in the drawings accompanying and forming a part of the specification. It is to be understood that I do not limit myself to the showing made by the said drawings and description, as I may adopt variations of the preferred form within the scope of the invention as set forth in the claims.

Referring to the drawings:

Fig. 1 is a view in side elevation of a vending machine incorporating the principles of the present invention. Portions of the figure have been

broken away to reduce its size, and other portions are shown in section, the better to reveal the operating mechanism.

Fig. 2 is a detail view in horizontal section, the plane of which is indicated by the line 2—2 of Fig. 1 and the direction of view by the arrows. Portions of this figure also are broken away to reduce its size.

Fig. 3 is a detail view in side elevation of portions of the operating mechanism showing those portions in the respective positions assumed thereby at a different period in the cycle of operation from that of the corresponding parts as illustrated in Fig. 1.

Fig. 4 is another view similar to Fig. 3 but showing the parts in still different positions.

Fig. 5 is a view partially in vertical section and partially in rear elevation of other portions of the operating mechanism. The plane of section is indicated by the line 5—5 of Fig. 1 and the direction of view by the arrows.

Fig. 6 is a view, largely schematic, showing one type of coin-control mechanism adaptable for use in connection with the vending machine of the present invention.

In terms of broad inclusion, the device of the present invention comprises a plurality of storage magazines for articles to be dispensed. Each of these magazines may contain a different article or a different brand or kind of the same article, or all magazines may contain identical articles so as to increase the total number that are available for vending. The dispensing mechanism makes it possible for the operator to receive articles from any one of the magazines when the releasing mechanism has properly been actuated. The releasing mechanism is of such a nature that its operation is variable to cause the machine to dispense different numbers of the article upon successive actuations, the number dispensed depending upon the manner in which the machine has been operated, as, for example, by depositing therein a coin of a certain denomination, the size of that coin determining the number of articles which the operator can cause to be dispensed.

More specifically described, my improved vending machine comprises an inner housing upon one side of which is mounted the releasing mechanism indicated in its entirety at 12 best illustrated upon Figs. 1, 3 and 4, which show the associated parts of the machine removed from the outside housing which has been omitted from the illustration in order to clarify the exposition. A plurality of preferably vertically

extending storage magazines 13 extend across the front of the machine, these magazines being of the proper proportions to accommodate the type of article to be dispensed. For example, the machine here illustrated is intended to dispense the conventional packages in which cigarettes are commercially made available to the public. Associated with each of the magazines 13 is a plunger 14, all of these plungers 14 extending across a horizontal platform 16 to make the knobs 17 at their outer ends accessible at the front of the machine.

The inner end of each plunger 14 carries a foot or pusher plate 18 which, when the associated plunger is in its retracted position as shown in Figs. 1 and 2, is disposed below the lowermost package 19 in the associated magazine 13. Hence the weight of all of the packages 19 in any one of the magazines 13 is imposed upon the foot 18 of the associated plunger 14. In order to permit one of the packages 19 to pass from its magazine 13 to a position wherein it is accessible to the operator of the machine, the associated plunger 14 must be pulled forward to remove the foot 18 from under that stack of packages 19, whereupon all of the packages in that magazine will drop on to a platform 21 which terminates at its inner edge 22 which is adjacent the after end of the lowermost package 19. The foot 18 then being at the outer or forward end of the lowermost package 19, that package can be caused to drop over the edge 22 of the platform 21 by pushing the plunger inwards, causing the foot 18 to engage the package and push it out from under the weight of the packages in the associated magazine. From the platform 21 that pushed package will drop into a compartment 23 in the lower part of the housing 11, where it is accessible to the operator. However, in order to secure the package the operator must open a door 24 which is connected to mechanism to be described in detail hereinbelow and which re-sets the releasing mechanism 12 for subsequent operation.

Each of the plungers 14 carries upon its inner end a wedge-shaped projection 31, the sharper end of which points toward the front of the machine and is disposed in proximity to a row of bars 32 extending transversely across the machine upon the table 16 and preferably extending just over the plungers 14. These bars 32 are transversely slidable in a suitable channel 33. Each bar 32, except those at the two sides of the machine, terminates at both ends in parallel oblique planes. One end of each of these bars 32, however, is relieved at its otherwise pointed end so that this relieved portion co-operates with the oblique end of the next adjacent bar 32 to present a substantially V-shaped notch 34 in alignment with the sharper end of the associated wedge-shaped projection 31. Accordingly, when one of the plungers 14 is pulled outwards, the associated wedge-shaped projection enters the proximal notch 34 and, by engagement with the oblique, unrelieved end of that bar 32 which extends clear across that plunger, thrusts that bar, and any other bars lying between it and the right-hand side of the machine as viewed from the front, farther toward the right-hand side. Thus it may be seen that if the bars 32 are prevented from moving to the right, none of the plungers 14 can be operated. That bar 32 which is proximal to the right-hand end of the machine terminates at its outer end in an oblique plane which is disposed at opposite inclination with respect to the inner end of that same bar 32. Accordingly when

this outermost bar 32 is moved to the right, it causes a longitudinally extending rod 36, the oblique end 37 of which is cooperatively associated with this oblique outer end of the outermost bar 32, to be thrust inward, i. e., toward the rear of the machine, carrying with it a lever 38, the lower end of which is pivoted upon the casting 11 as by a pin or screw 39 and the upper end of which is deflected toward the rear of the machine to present a finger or detent 41.

Rearward motion of the detent 41, and consequently of the bar 36, is normally prevented by the fact that one of a plurality of teeth 46 arranged about the periphery of a wheel 47 lies in the path of the detent 41; and inasmuch as such rearward motion of the rod 36 is necessary to permit the outermost bar 32 to move to the right, this interposition of one of the teeth 46 into the path of the detent 41 prevents movement of any of the plungers 14. However, each of these teeth 46 is rounded in such a manner that when the detent 41 engages the outer end of a tooth, the entire wheel 47 is urged to rotate in the direction of the arrow A. Such rotation of the wheel 47 will permit the detent 41 to enter one of the notches 48 which are presented in the periphery of the wheel 47 because of the spacing of the teeth 46.

The degree of rotation of the toothed wheel 47 which is necessary to permit such seating of the detent within a notch 48 is normally prevented through the expedient of a rack 51 mounted for vertical reciprocatory movement and a pinion 52 enmeshed therewith and mounted upon a transversely extending shaft 53 which also carries the toothed wheel 47. Both the pinion 52 and the toothed wheel 47 are rigidly secured to the shaft 53 so that the wheel 47 cannot turn unless the rack 51 moves vertically. The relationship between the pinion 52 and the rack 51 is such that the rack 51 must move upwards when the wheel 47 turns in the direction of the arrow A and upward movement of the rack 51 is normally prevented by means of a coin-releasable locking mechanism the details of which do not constitute an essential portion of the present invention, and are illustrated and described only as one example of several different types of releasable locking mechanism which can be employed. The coin control which is illustrated at 54 comprises a coin chute 56 into which coins of varied denominations can be inserted and has associated therewith mechanism for causing a cam 57 to be swung through a distance proportional to the size of the coin deposited. When a coin 58 is deposited in the chute 56 it comes to rest upon a shoulder 59 adjacent the bottom of the chute 56 and in registry with a reciprocable plunger 61. The coin 58 when in this position also lies within a yoke 62 in such a manner that when the plunger 61 is pushed inward it pushes against the coin 58 which in turn moves the yoke to the right as viewed upon Fig. 6, carrying with it the upper end of a lever 63 to which an extension 64 of the yoke 62 is connected by means of a pin 65 engaged within a slot 67 within the lever 63, which is rigid with the cam 57. The parts are so arranged that when the yoke 62 is pushed to the right the cam 57 is rotated in a clockwise direction as viewed upon Fig. 6. Moreover, as the cam 57 turns in this direction, its peripheral edge is removed farther and farther from the upper end of the rack 51 with the result that a greater degree of lift of the rack 51 is made possible by a greater degree of rotation of the cam 57. It is thus ap-

parent that the larger the coin 58 inserted into the coin slot 56, the greater the distance will be through which the rack 51 will be permitted to rise. The parts are so positioned, for example, that when a ten-cent piece is deposited, the cam 57 can be turned far enough to permit that degree of lift of the rack 51 which occurs when the wheel 47 turns through the number of degrees between corresponding parts of two adjacent teeth 46—when a twenty-five cent piece is deposited, the degree of lift of the rack 51 which is then made possible is proportionate to the angular separation of three of the teeth 46. If a fifty-cent piece is deposited, the permitted degree of lift of the rack is proportionate to, say, seven of the teeth; and if a dollar is deposited, the permitted degree of lift is proportionate to the actual separation of fifteen teeth. It should be understood that these figures are not recited in a limiting sense, but merely as exemplary, as various other proportions and respective numbers of teeth permitted to pass the detent for each size of deposited coin can be employed without departing from the principles of the present invention.

Any suitable means may be employed for retaining the coin 58 between the plunger 61 and the yoke 62, until the degree of rotation proportional to the size, and consequently also proportional to the denomination, of the particular coin 58 which has been inserted has been attained. For example, a coil spring 60 may be employed, under tension between the upper end of the lever 63 and a wall of the coin chute 56. However, the contractile resiliency of this spring 60 should not be enough to move the plunger 61. In other words, the spring 60 is strong enough to move the yoke 62 and the cam 57 back to initial position only after the plunger 61 has been withdrawn. Such withdrawal of the plunger 61, of course, will so decrease the pressure against the coin 58 that the coin will be free to drop from the bottom of the chute 56, with the result that the machine cannot again be operated until another coin has been deposited.

A coil spring 71, preferably disposed upon the shaft 53, is so engaged with the shaft and with a suitable rigid portion 72 of the frame that it continually urges the shaft 53, the pinion 52, and the toothed wheel 47 to rotate in that direction which results in upward movement of the rack 51. Also carried by the shaft 53, but free to rotate thereupon, is a locking plate 76. This locking plate 76 is provided with a weight 77 at the outer end of a projecting arm 78, whereby the locking plate 76 is continually urged by gravity to rotate upon the shaft 53, but in the direction opposite that in which the shaft and toothed wheel 47 are urged by the spring 71. Stop pins 79 and 81 limit upward and downward movement, respectively, of the arm 78. When the arm 78 is in its uppermost position, i. e., engaging the pin 79, a notch 82 in the periphery of the locking plate 76 is in registry with the detent 41, whereas when the lower stop pin 81 is engaged by the arm 78, the notch 82 is withdrawn from such registry.

The locking plate also carries a pawl 92, mounted upon another extending arm of the plate 76 as by a screw or pin 93. A coil spring 94 under tension between the pawl 92 and any suitable portion of the framework, continually urges the pawl 92 into that position in which it will be engaged by one of the teeth of the toothed wheel 47. For this purpose one of these teeth, here identified as tooth 91, is longer than the rest. The spring 71 is stronger than the spring 94, so

that when the pawl 92 engages the long tooth 91 the spring 71 will cause the locking plate 76 to turn until the upper stop pin 79 is engaged. Subsequently to such engagement no further turning of the toothed wheel can occur until the pawl 92 is withdrawn from engagement with the long tooth 91. Such withdrawal of the pawl 92 is effected through the expedient of a bell crank 96, on one end 97 of which the pawl 92 is mounted. The other end 98 of the bell crank extends downwards into the path of a shoulder 99 on the detent 41. The parts are so proportioned and arranged that when the detent 41 moves inwards toward the toothed wheel 47, the pawl 92 will be withdrawn from its engagement with its associated tooth 91 just after the detent 41 has entered the space between two of the teeth 46 and just prior to engagement of the detent 41 with the sloping surface of one of the teeth. Hence as the detent 41 moves further inwards, the wheel 47 is free to turn, permitting the detent 41 to enter the space between two adjacent teeth and complete its inward stroke.

It becomes apparent, therefore, that when the cam 57 has been removed from direct contact with the upper end of the rack 51, the rack 51 does not immediately rise, although it is urged to do so by the spring 71. Before such movement can occur, the pawl 92 must be withdrawn from its engagement with the tooth 91. As stated, such withdrawal accompanies motion of the detent 41 inwards towards the toothed wheel; such motion being the result of movement by the operator of the selected plunger 14, as explained. During the operation of the machine, which has been made possible by the operator having deposited the smallest coin 58 which is capable of operating the machine, the detent 41 will enter one notch, causing the toothed wheel 47 to turn far enough to bring the upper end of the rack 51 again into engagement with the cam 57. Therefore, should the operator withdraw the plunger, the spring 94 will rotate the locking plate 76, removing the notch 82 from registry with the detent 41; the result being that should the operator attempt to operate one of the plungers again, the detent will strike the periphery of the locking plate and thus will not be permitted to enter the notch between teeth 46 of the toothed wheel, even though the wheel has been held stationary, because of the engagement of the upper end of the rack 51 with the cam 57. This movement of the locking plate is possible because when the pawl released the tooth with which it was previously in engagement, the wheel 47 turned enough for the leading edge of that tooth to pass the point of the pawl, so that when the pawl descends again, it does not engage the tooth as before, but rides along the curved outer end of the tooth. Accordingly, the pawl 92 does not offer any resistance to the turning of the locking plate 76 by the spring 94. Of course the force of gravity acting upon the weight 77 cooperates with the spring 94 in turning the locking plate 76 to its locking position.

As stated, the package removed from any one of the magazines 13 drops into a chamber 23 wherein it is accessible to the operator only after he opens a door 24. This door 24 carries a lever 86 which is arranged to engage a second lever 87 and swing it in a clockwise direction as viewed upon Fig. 6, in such a manner as to cause the lever 87 to bear against a shoulder 88 on the rack 51 and press the rack 51 downward as the door 24 is opened. Hence, in order for the operator to

receive the packages to which he is entitled, he must first re-set the machine for subsequent operation, it being understood that such downward movement of the rack 51 results in turning the wheel 47 in the opposite direction. Furthermore the rack 51 will be carried considerably beyond its initial position, so that the long tooth 91 of the wheel 47 will be carried for some little distance beyond the pawl 92. During this return movement of the wheel 47, and as the long tooth 91 passes out from under the pawl 92, the pawl will drop down into position to be re-engaged by the long tooth 92, when the wheel again reverses its direction of movement, i. e., when the door 24 is closed, and the rack 51 again permitted to rise. Means are provided, however, for preventing any except the long tooth 91 from engaging the pawl 92 during resetting of the pay-out mechanism. This is easily accomplished by means of a stop 111 rigid with the frame of the machine and positioned to be engaged by the extended end 97 of the bell crank and raise the pawl out of the path of the shorter teeth 46 when the locking plate 76 is in locking position, but not out of the path of the long tooth 91. This ensures that only the long tooth 91 will engage the pawl 92 during resetting of the mechanism, so that the tooth wheel 47 will always return to the same starting position.

That the pawl 92 can engage the short teeth 46 when the plate 76 is in its unlocking position, but not when in locked position, is explained by the fact that when the plate is in its unlocking position, the pin 93 upon which the pawl 92 is mounted is rotated to the left and downwards from the position which the pin occupies when the plate 76 is in its locking position. Hence, the pawl 92 is lower when the plate 76 is in its unlocking position, and can engage any of the teeth 46 or 91, whereas when the plate 76 is in its locking position, the pawl 92 is raised so that it can engage only the long tooth 91. This engagement between the long tooth 91 and the pawl 92 makes it possible for the spring 71 to rotate the locking plate 76 in a counterclockwise direction, lifting the weight 77 to its uppermost position as illustrated on Figs. 1 and 3, and again bringing the notch 82 into alignment with the detent 41, placing the parts in position for subsequent operation.

When the machine receives a coin larger than that effecting the operation above described, the cam 57 will be turned farther than under the circumstances previously described, with the result that as the detent 41 is withdrawn from the notch 48 which it has been permitted to enter during the first actuation of the pay-out mechanism as described, the spring 71 is enabled to cause the wheel to turn still farther. The degree of rotation of the wheel under such circumstances is limited by the pawl 92 to such an extent that the next successive tooth 46 is stopped when it is in alignment with the detent 41. The engagement of the pawl 92 with one of the teeth 46 which results in such alignment between the next successive tooth and the detent is another function of the bell crank 96. It is apparent, therefore, that the pawl 92 cooperates with the detent 41 to constitute an escapement mechanism. While the pawl 92 is being raised out of engagement, this movement of the pawl is accompanied by entry of the detent 41 into one of the notches 48, this position being illustrated in Fig. 3. Before entry of the detent into the notch can be completed, however, the wheel 47 must turn slightly, so that when the detent is subsequently

withdrawn, permitting the pawl 92 to drop, the leading edge of the tooth which was last engaged by the pawl will have passed the pawl, and the pawl will drop into the path of the next successive tooth, stopping the wheel in such position that it is ready for entry of the detent into the next successive notch, i. e., with the rounded outer edge of the next successive tooth in registry with the detent 41. Such engagement between the pawl 92 and one of the teeth 46 serves the additional function of urging the locking plate 76 also to rotate in the same direction, with the result that so long as the wheel 47 is permitted to be rotated by the spring 71, i. e., until such time as the rack 51 again comes into contact with the cam 57, the notch 82 of the locking plate 76 will be retained in registry with the detent 41. Accordingly, when such condition obtains, the detent 41 can be reciprocated back and forth, each reciprocation causing one more package 19 to be dispensed and each reciprocation also permitting one more tooth 46 of the wheel 47 to pass the detent 41 until the rack 51 again comes into contact with the cam 57.

It is apparent, therefore, that the size of the coin 58 deposited within the coin chute 56 determines the distance through which the wheel 47 can be rotated before the plunger-locking mechanism re-sets; and, as stated, this also determines the number of packages 19 which the operator can receive without depositing an additional coin.

As far as actuation of the releasing or pay-out mechanism 12 is concerned, it makes no difference which of the plungers 14 is operated. The operator may, if he has purchased a plurality of the packages 19, operate one of the plungers until all of the packages to which he is entitled have been removed from the associated magazine 13; or, if he desires, he can operate different ones of the plungers 14. However, the number of such operations, regardless of whether they be all with one or with several of the plungers 14, is limited by the cam 57 and to an extent determined by the denomination of the coin which he has deposited.

As a safety feature, and in order to prevent unauthorized persons from improperly receiving articles 19 in the event of failure of certain parts of the machine, such for example as by breakage of the spring 101 which urges the arm 38 carrying the detent 41 to retracted position, i. e., to that position which interposes the end 37 of the rod 36 in the path of the bars 32, means are provided for sliding all of the bars 32 far enough to the right side of the machine to remove the notches 34 from alignment with their respective associated wedge-shaped projections 31. A leaf spring 102 is provided at the left-hand end of the machine and presses continually against the proximal bar 32 so that it continually urges all of the bars to move toward the right. In the event of failure of the spring 101, the rod 36 will be permitted to move to the right, as viewed upon Fig. 1, and all of the bars 32 will thus be permitted to move toward the right side of the machine, removing the notches 34 from that position thereof which is necessary for actuation of any of the plungers 14.

I claim:

1. In a vending machine, a storage magazine for articles to be dispensed, and dispensing mechanism comprising a plunger movable to release a predetermined number of said articles each time said plunger is reciprocated, a movable bar lying in the path of said plunger, means for

thrusting said bar aside when said plunger is moved, an oscillatively mounted detent operatively connected to said bar to be moved when said bar is thrust aside, a revolubly mounted wheel 5 having a plurality of teeth thereon spaced apart to present notches therebetween and having inclined edges engageable by said detent, one of said teeth normally lying in the path of said detent, yieldable means urging said wheel to rotate, 10 means normally holding said wheel against rotation and thereby locking said plunger, coin-operated means for releasing said wheel-holding means and for limiting the extent of movement of said wheel after release to permit rotation of the wheel through a predetermined arc, 15 movable means lying in the path of said detent to hold it out of said notches, means holding said detent-holding means in inoperative position until said wheel has turned through said arc, and escapement means operative upon withdrawal of said detent from one of said notches to position the wheel with its next 20 successive notch for entry of said detent thereinto when said wheel is free to rotate that far.

2. In a vending machine, a storage magazine for articles to be dispensed, and dispensing mechanism comprising a plunger movable to release a predetermined number of said articles each time said plunger is reciprocated, an oscillatively mounted detent operatively connected to said plunger to be moved thereby when said plunger is moved, a revolubly mounted wheel having a plurality of teeth thereon spaced apart to present notches therebetween and having inclined edges, 25 one of said teeth normally lying in the path of said detent, yieldable means urging said wheel to rotate, means normally holding said wheel against rotation and thereby locking said plunger, coin-operated means for releasing said wheel-holding means and for limiting the extent of movement of said wheel after release to permit rotation of the wheel through a predetermined arc, a locking plate mounted for oscillatory rotational movement adjacent said wheel and having a notch therein, a pawl carried by said locking plate and releasably engaging one of said teeth to hold the locking plate with its notch in registry with said detent, means urging said locking plate to rotate in the direction opposite that in which said wheel is urged by its associated urging means, means for withdrawing said pawl from operative position when said detent moves into one of said notches, and means for moving said pawl back into the path of said teeth upon withdrawal of said detent from said notch, said wheel-urging means being adapted to rotate said wheel upon release thereof by said detent to bring the next successive notch into registry with said detent before the notch on said locking plate moves out of registry therewith when said wheel is free to rotate that far.

3. In a vending machine, a storage magazine for articles to be dispensed, and dispensing mechanism comprising a plunger movable to release a predetermined number of said articles each time

said plunger is reciprocated, an oscillatively mounted detent operatively connected to said plunger to be moved thereby when said plunger is moved, a revolubly mounted wheel having a plurality of teeth thereon spaced apart to present notches therebetween, one of said teeth normally lying in the path of said detent, yieldable means urging said wheel to rotate, means normally holding said wheel against rotation and thereby locking said plunger, coin-operated means for releasing said wheel-holding means and for limiting the extent of movement of said wheel after release to permit rotation of the wheel through a predetermined arc, movable means lying in the path of said detent to hold it out of said notches, 10 means holding said detent-holding means in inoperative position until said wheel has turned through said arc, and escapement means operative upon withdrawal of said detent from one of said notches to position the wheel with its next 15 successive notch for entry of said detent thereinto when said wheel is free to rotate that far.

4. In a vending machine, a storage magazine for articles to be dispensed, and dispensing mechanism comprising means movable to release a predetermined number of said articles each time said releasing means is actuated, a detent operatively connected to said releasing means to be moved thereby each time said releasing means is actuated, a pair of movably mounted members disposed adjacent said detent, one of said members having a plurality of teeth spaced apart to present notches adapted to receive said detent successively therein and thus permit movement of said detent, means operative upon withdrawal of said detent from one of said notches for advancing said toothed member to position said toothed member for entry of the detent into the next successive notch, releasable means locking said toothed member against movement, coin-operated means for releasing said locking means and for limiting the extent of movement of said toothed member after such release, and means for moving the other of said members into the path of said detent, said moving means becoming operative upon withdrawal of said detent from the last of said notches before the limit of movement of said toothed member is reached, said limiting means being variable whereby different numbers of said notches can be entered successively by said detent before the limit of movement of said toothed member is reached.

5. In a vending machine, a storage magazine for articles to be dispensed, and dispensing mechanism comprising means movable to release a predetermined number of said articles each time said releasing means is actuated, a detent operatively connected to said releasing means to be moved thereby each time said releasing means is actuated, a pair of movably mounted members disposed adjacent said detent, one of said members having a plurality of teeth spaced apart to present notches adapted to receive said detent successively therein and thus permit movement of said detent, means operative upon withdrawal of said detent from one of said notches for advancing said toothed member to position said toothed member for entry of the detent into the next successive notch, releasable means locking said toothed member against movement, coin-operated means for releasing said locking means and for limiting the extent of movement of said toothed member after such release, and means for moving the other of said members into the path of said detent, said moving means becoming operative

upon withdrawal of said detent from the last of said notches before the limit of movement of said toothed member is reached.

6. In a vending machine, a storage magazine 5 for articles to be dispensed, and dispensing mechanism comprising means movable to release a predetermined number of said articles each time said releasing means is actuated, a detent operatively connected to said releasing means to 10 be moved thereby each time said releasing means is actuated, a movably mounted member disposed adjacent said detent, a plurality of teeth carried by said member and spaced apart to present notches adapted to receive said detent successively therein and thus permit movement of said detent and actuation of said article-releasing means a number of times corresponding to the number of notches entered by said detent, releasable means holding said member against 15 sufficient movement to permit entry of said detent to a notch, coin-operated means for releasing said member-holding means and for limiting the extent of movement of said member after such release, means operative upon removal of said 20 detent from one of said notches for moving said member into position for said detent to enter the next successive notch, said member-moving means being operative only until said member has reached the extent of its movement as determined 25 by said limiting means, and means for restraining said detent from re-entering the last of said notches after said member has reached said limit of its movement.
7. In a vending machine, a storage magazine 30 for articles to be dispensed, and dispensing mechanism comprising means movable to release a predetermined number of said articles each time said releasing means is actuated, a detent operatively connected to said releasing means to be 35 moved thereby each time said releasing means is actuated, a movably mounted member disposed adjacent said detent, a plurality of teeth carried by said member and spaced apart to present notches adapted to receive said detent successively therein and thus permit movement of said detent into plunger-releasing position and actuation of said plunger a number of times corresponding to the number of notches entered by said detent, releasable means holding said member against sufficient movement to permit entry 40 of said detent to a notch, coin-operated means for releasing said member-holding means and for limiting the extent of movement of said member after such release, means operative upon removal 45 of said detent from one of said notches for moving said member into position for said detent to enter the next successive notch, said member-moving means being operative only until said member has reached the extent of its movement as determined 50 by said limiting means, and means for restraining said detent from re-entering the last of said notches after said member has reached said limit of its movement, said limiting means 55

being variable whereby different numbers of said notches can be entered successively by said detent before the limit of movement of said toothed member is reached.

8. In a vending machine, a storage magazine 5 for articles to be dispensed, and dispensing mechanism comprising a plunger movable to release a predetermined number of said articles each time said plunger is actuated, a detent operatively connected to said plunger to be moved 10 thereby each time said plunger is actuated, a member movably mounted in the path of said detent and having a plurality of notches therein adapted to be entered successively by said detent, said member holding said detent against 15 movement by said plunger except when said detent enters one of said notches, releasable means holding said member with all of its notches out of registry with said detent, and coin operated means for releasing said holding means and for 20 advancing said notched member with respect to said detent each time said plunger is actuated, and means limiting the number of notches said detent can enter.

9. In a vending machine, a storage magazine for 25 articles to be dispensed, and a dispensing mechanism comprising means for releasing a predetermined number of said articles each time said article-releasing means is actuated, a detent operatively connected to said releasing means to be 30 reciprocated each time said releasing means is actuated, a member movably mounted in the path of said detent and having a plurality of notches therein, means urging said member to advance whereby to dispose said member with its notches 35 successively in position for entry of said detent thereinto, and escapement means actuated by said detent whereby advance of said member each time said detent is reciprocated is limited to the extent required for the next successive one of 40 said notches to move into position for entry of said detent thereinto.

10. In a vending machine, a storage magazine for articles to be dispensed, and a dispensing mechanism comprising means for releasing a 45 predetermined number of said articles each time said article-releasing means is actuated, a detent operatively connected to said releasing means to be reciprocated each time said releasing means is actuated, a member movably mounted in the 50 path of said detent and having a plurality of notches therein, means urging said member to advance whereby to dispose said member with its notches successively in position for entry of said detent thereinto, escapement means actuated 55 by said detent whereby advance of said member each time said detent is reciprocated is limited to the extent required for the next successive one of said notches to move into position for entry of said detent thereinto, and means for varying the 60 number of notches said detent can enter.

LEE M. MONINGER.
